UNITED STATES PATENT OFFICE.

HENRY E. MUCHNIC, OF ATCHISON, KANSAS, ASSIGNOR TO THE LOCOMOTIVE FINISHED MATERIAL COMPANY, OF ATCHISON, KANSAS, A CORPORATION OF KANSAS.

RAILWAY HIGHWAY CROSSING.

Application filed May 6, 1927. Serial No. 189,195.

My invention relates to crossing structures for use at the grade crossings of highways by railways whereby a substantially flush crossing is provided consisting of suitable sized metallic units or sections possessing the requisite strength and capable of easy installation and ready removal when occasion arises as for example for track repair.

My invention also has for its object a crossing composed of a comparatively small number of sections, or units of self supporting type and of a self-retaining construction, so that spiking or fastening of the units or sections to the cross-ties of the track is unnecessary and need for special bolt holes in the rails is also obviated.

My improved construction, therefore not only permits application of the elements intermediate of the rails without regard to the location of the cross-ties, but also enables similar units or sections to be used as an approach to the track; the construction providing for proper clearance on the inside of the rails for the wheel-flanges, while at the same time presenting a top surface affording the necessary traction.

The above recited objects and others, as well as the advantages inherent in the construction, will all be readily comprehended from the detailed description of the accompanying drawings, wherein:

Figure 1 is a plan view of my improved crossing as applied to a single track.

Figure 2 is a cross sectional view taken substantially on the line 2--2 of Figure 1.

Figure 3 is a longitudinal sectional view of a section intermediate of the rails, as for example on the line 3--3 of Figure 1.

Figure 4 is a plan view of a crossing involving a modified form of my invention; portions of two track-rails being shown and one end of the crossing shown broken away.

Figure 5 is a cross section, taken substantially on the line 5--5 of Figure 4.

Figure 6 is a detail perspective view of one of the spacer members employed in the construction shown in Figure 5.

Figure 7 is a cross-section of a portion of crossing adjacent to one rail, showing a modified form.

In the exemplification of the invention, as disclosed in the first figures of the drawings, 10, 10 represent the running or track rails of

T-shape or the usual well known railroad rail construction, mounted on the usual cross-

ties 11 which generally extend beyond the outer sides of the rails.

The rails are frequently mounted immediately on tie-plates secured to the cross-ties by the same spikes which secure the rails to the ties, but as my improved construction is entirely independent of the rail supporting and fastening means, the tie-plates and rail joint forming elements are not shown.

The crossing and especially that portion located intermediate of the rails 10, 10 is preferably made in portable sections of suitable and more or less uniform lengths and also preferably consists of a number of sections disposed side by side intermediate of the rails constituting what may be termed an intermediate section 12, and two side sections 13, 13, see Figure 2.

The side sections 13, as shown in Figure 2, are identical in construction and each consists of a number of T-shaped beams or inverted rail elements 14, the heads 15 whereof rest on the cross-ties 11, while the flanged base portions constitute the upper crossing surface.

The rails are held in proper inverted position and spaced relation by spacing members 16 preferably of metal to provide the requisite strength and also prevent rapid deterioration. In the particular exemplification illustrated in Figures 1 and 2, these spacers are shown in the nature of hollow metallic filler blocks, of substantially rectangular configuration in cross-section. These spacers may be of any predetermined length, preferably in comparatively short block form; any suitable number being employed to a given length section, for example, say four spacers to every ten feet length of section. The specific spacers of the exemplification have top and bottom portions of somewhat greater width than the vertical depth of the sides which contact with the webs of the inverted rails 14; the juncture between the sides and the top and bottom being slightly curved to conform with the side contour of the inverted rails 14 and also preferably contact at bottom with the head portion of the rails 14 and at top with the lower surface of the flanges

of the rails. It is apparent that the supporting surface formed by the rail flanges is reinforced by the spacer members. The transverse dimensions of the spacing members 16 are preferably slightly greater than

the width of the base of the rail members 14, in order to provide a slight space between the opposing edges of adjacent rail members 14, as shown at 17. This provides an interrupted upper surface which affords gripping with increased traction and prevents slipping.

10 The spacer members and the vertical web portion of the T-shaped members at points where the spacers are to be located are provided with holes therethrough to receive the fastening bolts or rods 18.

15 In order that the construction may be portable and readily handled, the crossing is preferably made in sections as previously mentioned, with the intermediate section 12, in the particular exemplification shown consisting of a pair of T-shaped members or 20 parallelly arranged inverted railroad rails of desired length secured together with hollow blocks or spacer members 16 therebetween at predetermined spaced points intermediate of and at the ends of the inverted rail members; the elements being secured together by short rods or bolts 18; while the side sections 13 are shown consisting of three inverted rail members 14, spacedly held together by the intermediate hollow blocks or 25 members 16 which form contact with the entire web portion of the rail members.

30 The side sections 13, however, are intended to provide a sufficient wheel-flange receiving space on the inner sides of the two rails of the track and I therefore show these side sections 13 also involving a narrower hollow block or spacer element 19—which is 35 practically half the width of the elements 16—one flat side bearing against the vertical web of the outer rail element 14, while 40 its opposite flat side has the flanged base of a horizontally or sidewise disposed rail element 20 bearing there-against. The various elements 14, 16, 19 and 20 are secured together by rods 18 and the ball or head of the rail member 20 is adapted to have bearing relation with the side of the track rail 10 beneath the ball or head thereof. In 45 order to prevent short circuiting of the signalling and other circuits which are completed through the rails, the ball or head 50 of the spacing rail element 20 is preferably provided with suitable insulating material as at 22.

55 As previously stated, the crossing, especially between the rails of a track, is made in sections not only of predetermined length and arranged in end to end relation in keeping with the width of the crossing or highway, but in sections to be arranged parallel 60 with each other or side by side relation intermediate of the rails as shown in Figure 2. I prefer that the crossing intermediate of the rails of a track consist of a number of sections, as for example three sections as 65 shown, to enable ready handling; the sec-

tions, as disclosed in Figure 1 being all of equal length.

At the left hand end of Figure 2 I show a portion of the crossing elements employed intermediate of adjacent parallel tracks. 70 These elements, like those previously described, consist of the T-shaped beams or inverted rail members 14, which may be arranged on the outer ends of the cross-ties 11, and the beams held in spaced relation by the 75 spacers 16. The T-shape beams or inverted rail members adjacent to the outer sides of the track rails are maintained in position by the spacer elements or blocks 23 substantially similar in construction to the spacing 80 elements 16, except that they are of narrow width and provided with the upper and lower sloping surfaces 24 in order that the rail engaging side 25 may contact with the web of the track rail 10 and be disposed beneath the ball or head thereof while also resting on the base flange of the track rail 10. It is apparent that the construction shown to the 85 left in Figure 2 may also constitute the approach portion of the crossing.

90 I prefer to have the opposite sides of the crossing, namely the outer ends of the crossing sections, taper off toward the bottom of the various members, as more clearly shown in Figure 3 where the outer end of the T-beam or inverted rail member 14 is cut away or beveled at an angle as shown at 26.

Where the beams are tapered as just described, the spacing members 27, arranged intermediate of the beams adjacent the outer ends, are also preferably made with a tapered or beveled end, as shown at 28 in Figure 3, to conform with the bevel of the T-beam or rail member 14.

95 In Figures 4, 5 and 6, I show a modified form of my improved crossing as well as a modification in its arrangement or placing, especially between the track rails 10, 10. The crossing disclosed in these figures, like that shown in the previous figures, consists 100 of the main supporting surface members in the form of the T-beams or inverted rails 14 held in proper position and spaced relation by the spacing elements or blocks 29. These 105 spacers 29 are substantially identical with the spacing members 16 previously described, except that the top surface of these spacing blocks 29 is shown provided with an upstanding lug or lip 30 adapted to extend intermediate of the opposing longitudinal faces of the flange portions of the inverted rails 14, thereby providing a gripping 110 top surface to the crossing for the purpose of traction.

115 The crossing between the rails, like in 120 the previously described construction, is preferably made in units 31, 31 which constitute the side sections and unit 32 which constitutes an intermediate section. The crossing construction shown in Figures 4 125

and 5 has the inner longitudinal sides of the sections 31 each provided with a spacing block or member 33 practically consisting of a half of the spacing members 29, as shown in Figure 6, and provided with the vertical web or wall 34 formed integral with the upstanding lug 30. The intermediate section or unit 32, along its longitudinal sides, is also preferably provided with a corresponding half-sized spacing member or block 33; and the flat vertical webs 34 of the two half sections of the spacing block are arranged in face to face relation, as shown in Figure 5. The outer longitudinal sides 15 of the side sections or units 31 in this construction are provided with a spacing block and rail-engaging member 35, the main body portion whereof, like spacers 33, practically consists of a half of the spacing blocks previously described and preferably 20 without the upstanding lug 30. The outer vertical face of the member 35 is provided with a laterally disposed arm 36 terminating in a vertically disposed shoe 37 25 forming somewhat to the contour of the adjacent side or face of the track rail 10 in order to fit in between the ball or head of the rail and the flanged base portion thereof. The shoe portions 37, in order to prevent any 30 short circuiting of the track circuits are provided with suitable insulation shown at 38.

The widths of the respective sections are, of course, made in keeping with the distance between the rails of a track; the respective sections in the exemplification involving three T-beams or inverted rail members 14 having intermediate spacing members 29 with one longitudinal side provided with the half spacing member 33, while the other longitudinal side consists of the spacing and rail engaging member 35,—while the intermediate section in this construction is shown consisting of three T-beams or inverted rail members 14 held in spaced 45 relation by spacing members 29 and each longitudinal side provided with a half-spacing block or member 33; the T-beams 14 and the intermediate spacing members 29 of the respective sections being preferably secured together by suitable long rods or bolts 18.

The T-beams or inverted rail members, which may be of any pre-selected length to permit easy handling, are preferably arranged longitudinally of the track rails so as to provide staggered joints. As shown in Figure 4 where the T-beams of the side sections 31 adjacent to the track rail are arranged to provide the abutting joint at 39, while the next T-beam or inverted rail member 50 of the aligned side sections 31 provides abutting relation at the point indicated at 40; the respective abutting joints throughout the crossing being preferably staggered as shown in Figure 4.

It will be understood that the spacing

members, as in the previously described construction, preferably consist of short blocks or members arranged at predetermined points throughout the length of the T-beams or inverted rail members, namely preferably 70 at the ends and at a suitable intermediate point or points. The rail members 14 at the ends thereof, namely at the sides of the crossing, are also preferably tapered off as shown in Figure 3, in order that no abrupt 75 angle may be presented in the direction of an approaching train, and as a result any dangling chain or air line connection may ride upward on the sloping beveled surface.

Instead of employing the hollow spacing 80 blocks heretofore described, the T-beams or inverted rail members 14 may be held in proper spaced relation and proper upright position by small blocks of I-beam construction in cross section, with the flanges thereof 85 disposed against the vertical web portions of the inverted rails intermediate of the ball and flanged portion thereof as shown in Figure 7 at 41; the spacing members 41 and inverted rail members of each section being 90 secured together in any suitable manner, as for example by the long bolts or rods 42 disposed through the flanges of the I-beam blocks and the webs of the inverted rail members. 95

The constructions that have been shown will provide a railway highway crossing formed of portable sections while at the same time producing a self-supporting crossing 100 adapted to maintain its position without necessity for special fastenings to the cross ties or to the track rails. This not only enables the crossing to be readily installed at any desired point, but also permits the quick removal of the crossing in sections or in its entirety for the purpose of 105 replacing cross ties or repairing the track-way, bond wires, etc. should occasions require.

I have shown what I believe to be the best embodiments of a self sustaining crossing which have been described in terms employed merely as terms of description and not as terms of limitation, as certain structural modifications may be made without, however, departing from the spirit of my invention. 110

What I claim is:

1. A railroad highway crossing comprising a plurality of parallelly disposed T-shaped members arranged to present a flat upper surface, spacing members intermediate of the vertically disposed sides of adjacent T-shaped members, and fastening means disposed transversely through the T-shaped 120 members and the spacing members. 125

2. A railroad highway crossing comprising a plurality of supporting members, a plurality of spacer members arranged intermediate of the supporting members in bear- 130

ing relation therewith intermediate of the upper and lower ends thereof, and removable tie-means disposed transversely through the supporting members and the spacer members.

3. A railroad highway crossing of pre-arranged portable units each comprising a plurality of supporting members consisting of T-shaped rail sections, uniform spacer members having vertically disposed wide sides arranged in bearing relation throughout the web portions of said rail sections beneath the tops thereof, and removable tie-means disposed transversely through the supporting members and the spacer members.

4. A railroad highway crossing comprising in combination with a pair of rails between which the crossing is arranged, supporting members consisting of T-shaped members of predetermined lengths, uniform spacer members arranged at prearranged points intermediate of the supporting members, laterally extending portions on the spacer members opposite the rails disposed in a plane beneath the tops of the rails for maintaining the crossing in spaced relation with the rails to provide wheel-flange space, said portions adapted to have insulated bearing relation with the webs of the rails, and tie-means whereby said members are secured together.

5. A railroad highway crossing composed of inverted rail sections arranged in parallel spaced relation with the rails, spacer members arranged at spaced points intermediate of the web portions of adjacent rail sections, horizontally disposed elements intermediate of the opposing faces of the outer side rail sections and the track rails whereby wheel-flange spaces between the track rails and the crossing are provided, and common tie-means whereby said rail sections, spacer members and said elements are bound together in preselected number to form crossing sections of predetermined dimensions.

6. In combination with a pair of track rails, a crossing composed of self-supporting sections, each section comprising a plurality of T-shaped beams arranged in parallel spaced relation with each other and with said track rails, spacer blocks having wide vertical sides bearing against the vertical por-

tions of adjacent beams adapted to maintain the upper horizontal portions of said beams in slight spaced relation, the side crossing sections on the rail sides having laterally projecting elements terminating in insulated rail-web abutting heads for holding the crossing sections in spaced relation with the track-rails, and tie-means whereby said beams, spacer blocks and elements are secured together.

7. A railroad highway crossing composed of self-supporting sections each comprising a plurality of T-shaped beams arranged in parallel relation disposed lengthwise of the track rails, spacer members with wide sides bearing against the vertical portions of adjacent beams adapted to maintain the upper horizontal portions of said beams in slight spaced relation, said spacer members having upstanding projections disposed between the upper horizontal portions of said beams.

8. A railroad highway crossing comprising a plurality of parallelly arranged self-supporting beams disposed lengthwise of the track rails, and a plurality of spacer members arranged intermediate of the beams in bearing relation with the sides thereof.

9. A railroad highway crossing comprising prearranged units each consisting of supporting beams, spacer members arranged between the beams in bearing relation with the sides thereof, means whereby the beams and spacer members of each unit are secured together, spacer blocks intermediate of the sides of the beams of adjacent units, and rail-engaging elements adapted to bear against the sides of the beams of the side units and the webs of the adjacent rails of the track.

10. A railroad highway crossing comprising a plurality of elongated self-supporting beams arranged in parallel relation and provided with supporting bases and laterally enlarged upper surfaces, spacer members disposed between the beams in bearing relation with the sides thereof between the bases and enlarged upper surfaces, and rail-engaging members in bearing relation with the side beams and with the sides of the adjacent rails, said last mentioned rail-engaging members being formed to provide wheel flange spaces.

HENRY E. MUCHNIC.
